UNITED STATES PATENT OFFICE.

CHARLES H. MONROE, OF CARBONDALE, PENNSYLVANIA.

AUTO-AIR PIPE COUPLING.

1,131,323.

Specification of Letters Patent.

Patented May 2, 1916.

Application filed October 23, 1915. Serial No. 37,533.

To all whom it may concern:

Be it known that I, CHARLES H. MONROE, a citizen of the United States, residing at Carbondale, in the county of Lackawanna and State of Pennsylvania, have invented new and useful Improvements in Auto-Air Pipe Couplings, of which the following is a specification.

The invention relates to an improvement in automatic couplers, being directed to a means for the automatic connection of the air pipes of cars during the coupling operation of said cars.

The construction provides for the interfitting of the meeting ends of couplers and the construction of such ends to provide a tight joint and at the same time through automatically operated mechanism to open valves to permit communication between the coupled ends.

The invention in the preferred form of details will be described in the following specification, reference being had particularly to the accompanying drawings, in which:

Figure 1 is a plan of the improved coupler; Fig. 2 is a horizontal section of the same; Fig. 3 is a vertical section on the line 3-3 of Fig. 1; Fig. 4 is a perspective view of one of the heads; Fig. 5 is a view in elevation of the air pipe and connections immediately adjacent the couplers; Fig. 6 is a view similar to Fig. 5, but on an enlarged scale, certain parts of Fig. 5 being omitted.

In constructing the improved coupler it is of course understood that the coöperating heads are of identical construction and hence the detail description of one will suffice for both.

The head proper includes a head plate 1 from which extends a cylindrical casing 2 terminating at the forward end in an inclined face 3, the face terminating at the respective ends inwardly of the annular surface of the casing, presenting shoulders 4 and 5, at direct right angles to the axis of the casing and respectively at the forward and rear ends of the inclined face. The shorter wall of the casing is extended in the form of a guide 6 which extends beyond the casing proper and is provided at its extreme forward end with a relatively outwardly inclined lip 7. The respective lips of the coöperating heads thus form opposing guides for centering the casings in their coupling coöperation thereby accurately outlining

said members as they approach each other. The air pipe 8 passes through the head plate 1 and communicates with a pipe section 9 arranged within the casing 2, said pipe 9 opening through an inclined face 3 of the casing and thus presenting an opening 10 at an inclination to the axis of the casing and preferably provided with a suitable rubber gasket 11. Each guide plate 6 is provided with a guide projection 12. Below the guide projection 12 and arranged on the casing 2 are supported clamp blocks 13 arranged to receive the advance end of the casing and guide the same to proper position, the blocks 13 serving further to clamp the end of the casing to hold it rigid in use.

The pipe 9 is provided with a valve 14 of any appropriate type designed to be operated through a lever 15. This lever projects beyond one side of the casing, and the guide projection 12 is provided with a triangular trip dog 16 arranged in the path of travel of the arm 15 of the opposing head. The dog 16 normally presents one squared surface 17 in spaced parallel relation to what may be termed the rear wall 18 of the band 12, and as the couplers approach the coupling coöperation the lever 15 rides against the inclined face of the dog 16, displacing the latter and riding into engagement with the rear wall 18 of the band, stopping the movement of the lever and, on a further movement of the coupling head, moving the lever to open the valve. After initial displacement of the dog by the lever, the former, by gravity, returns to normal position, presenting the square surface 17 in the path of movement of the lever. In this connection it is to be noted that the space between the wall 18 of the band and the square surface 17 of the dog is materially greater than the size of the lever, whereby provision is made for permitting the valve to remain open a short time in the event of accidental separation or breaking apart of the cars before the closing operation of the lever, thereby providing for a setting of the brakes to an appreciable extent. In the uncoupling operation it is understood that the lever engages the square face 17 of the dog, and the latter held against movement in this direction by a stop 19 will prevent movement of the lever with the head, causing the lever to be moved to a valve closing position.

The train pipe immediately beyond the

head is formed with a ball and socket joint 20 to permit comparatively free motion in order to compensate for the movement of the cars. It is held rigid by four springs 21, which through the medium of pin and slot connections 21' are yieldingly connected with a collar 22 secured upon the train pipe, the opposite ends of the springs being also connected to a collar 23, rearwardly beyond the joint 20, the collar 23 being secured at its diametrically opposite points only to the train pipe, in order to permit two of the springs to yield while the other two are under tension. The train pipe in rear of the joint 20 is provided with an emergency angle cock 24 which may be used for switching cars while the train line is changed. The train pipe is also connected with a T-connection 25 arranged to 10 permit the ordinary hose connection to be made thereto, so that a car equipped with the coupler may be connected to one not so equipped. The train pipe in rear of the emergency angle cock is provided with a lateral portion 26 connected by swing joints 27 with the train proper and with that portion extending forward to the coupler. In advance of the lateral portion the train pipe is held under spring tension, through 15 the medium of a spring 28 encircling the same and bearing at the inner end against a hanger 29 dependent from the car body and at the forward end against the collar 30 carried by the train pipe proper. This 20 insures a sufficient tension on the train pipe when the couplers are connected to maintain a tight connection.

The operation of the coupler will be apparent from the drawing, it being understood that as the heads approach they will be guided into alining positions and the movement continued until the ends of the casings are engaged by the clamps 13 and the lever 15 operated to open the valves. 25 On separation of the couplers the valve will be automatically closed in an obvious manner.

What is claimed is:

1. An automatic air coupler comprising a coupling head having an inclined bearing face, the air pipe opening through said face, a guide plate and clamp members carried by the head to receive and engage the

opposing head, a valve in the air pipe, a lever for operating the valve and a dog carried by the head to engage the lever of the opposing head in the operation of the head to close the valve. 55

2. An automatic air coupler comprising a coupling head having an inclined bearing face, the air pipe opening through said face, a guide plate and clamp members carried by the head to receive and engage the opposing head, a valve in the air pipe, a lever for operating the valve and a dog carried by the head to engage the lever of the opposing head in the operation of the head to close the valve, a band carrying the dog, said band being engaged by the lever in the coupling movement of the heads to open the 60 valve. 65

3. An automatic air coupler comprising a coupling head having an inclined bearing face, the air pipe opening through said face, a guide plate and clamp members carried by the head to receive and engage the opposing head, a valve in the air pipe, a lever for operating the valve and a dog carried by the head to engage the lever of the opposing head in the operation of the head 70 to close the valve, a band carrying the dog, said band being engaged by the lever in the coupling movement of the heads to open the 75 valve, said band and dog being spaced apart to permit the slight operating movement of the heads without affecting the dog. 80

4. An automatic air coupler comprising a coupling head having an inclined bearing face, the air pipe opening through said 90 face, a guide plate and clamp members carried by the head to receive and engage the opposing head, a band carried by the guide plate, a triangular dog pivoted thereon, said dog presenting a squared surface to 95 one wall of the band, and a valve lever mounted on the head in a position to engage the dog of the opposing head in the coupler operation.

In testimony whereof I affix my signature in presence of two witnesses.

CHARLES H. MONROE.
